UNITED STATES PATENT OFFICE.

FREDERICK SINCLAIR CORRIGAN, OF TORONTO, ONTARIO, CANADA, ASSIGNOR, BY
MESNE ASSIGNMENTS, TO GENERAL STEEL WARES LIMITED, OF TORONTO, CANADA.

SINK DRAINAGE BOARD.

Application filed October 30, 1926, Serial No. 145,287, and in Canada October 29, 1926.

This invention relates to boards such as employed in connection with sinks for the drainage of dishes and which usually rest at one end on the sink and are supported on a 5 bracket or brackets extending from the wall to which the sing is connected. In the case of metal drainage boards, it is difficult to satisfactorily secure the board to the supporting bracket or to hold it firmly down 10 against the edge of the sink, and my object is to devise simple and effective means for forming such connections.

I attain my object by means of the constructions hereinafter described and illustrated in the accompanying drawings in which

Fig. 1 is an end elevation of a drainage board constructed in accordance with my invention and shown in position on a sink; 20 Fig. 2 a front elevation, partly in section, of the same;

Fig. 3 a plan view of the underside and Fig. 4 a cross section of the drainage board.

25 In the drawings like numerals of reference indicate corresponding parts in the different figures.

1 is a stamped metal drainage board of ordinary type. At the under side of the 30 board are secured loops 2, preferably rectangular in form, bent up from a strip of metal and provided with lugs 3 welded to the underside of the board. These pairs of loops are so positioned relative to the depending flange 4 of the board that wooden cleats 5 may be inserted into the loops in the following manner.

One end of the cleat is pushed well through one of the loops from the inner side 40 until its other end clears the other loop. The cleat may then be drawn back to engage in said second loop and held in position in engagement with both loops by a nail or screw. In order that this may be done each 45 cleat is made not longer than the distance between the inner edge of the flanges and the inner edge of the loop remote therefrom. The cleat 5 at the outer end of the board, when the board is in use, is secured by means 50 of screws 12 to the bracket 6, adapted to be secured to the wall against which the sink 7 is secured. The cleat 5 at the inner end of the board provides means whereby the drainage board may be secured to the edge 55 of the sink. One or more clamp members

are provided, each clamp member being formed with a hook 9 at its inner end to engage under the rim of the sink while the other end 10 is bent to engage the under surfaces of the drainage board when the center 60 of the clamp is drawn up to the cleat by means of the screw 11.

The constructions described, as will be seen, provide means whereby the drainage board may be connected very securely to 65 the sink and wall without any traces of such connections showing at the upper side of the board.

What I claim is:

1. A sheet metal drainage board for sinks 70 having a plurality of pairs of alined metal loops permanently secured to its under surface; wooden cleats adapted to be slipped into and held by said loops; a clamp member; a screw for securing the clamp member to one of said cleats with one end engaging under the edge of a sink on which one end of the board is rested; a wall bracket adapted 75 to be secured to a wall; and screws for removably securing the wall bracket to the 80 other cleat.

2. A sheet metal drainage board for sinks having a pair of alined metal loops permanently secured to its under surface adjacent one end; a wooden cleat adapted to be 85 slipped into and held by said loops; a wall bracket separate from said cleat and having a wall engaging part and a part adapted to be secured to the cleat; and screws for removably securing the wall bracket to the 90 cleat.

3. A sheet metal drainage board for sinks having a pair of alined metal loops permanently secured to its under surface adjacent one end; a wooden cleat adapted to be 95 slipped into and held by said loops; a clamp member; a screw for securing the clamp member to said cleat with one end engaging under the edge of a sink on which one end of the board is rested; and means for supporting the outer end of the board.

4. A sheet metal draining board provided with a depending flange; a pair of alined metal loops permanently secured to its under surface adjacent one end; a wooden cleat adapted to be slipped into and held by said loops, the cleat being not longer than the distance between the inner edge of the flange and the inner edge of the loop remote therefrom so that the cleat may be in- 105 110

serted through one of the loops from the inner side until it clears the other loop and may be drawn back to engage in said other loop; and a wall bracket adapted to be removably secured to the cleat and the wall.

5. A sheet metal draining board provided with a depending flange; a pair of aligned metal loops permanently secured to its under surface adjacent one end; a wooden cleat adapted to be slipped into and held by said loops, the cleat being not longer than the distance between the inner edge of the flange and the inner edge of the loop remote

therefrom so that the cleat may be inserted through one of the loops from the inner side until it clears the other loop and may be drawn back to engage in said other loop; a clamp member adapted to be secured to said cleat with one end engaging under the edge of a sink on which one end of the board is rested; and means for supporting the outer end of the board.

Signed at Toronto, Canada, this 13th day of October, 1926.

FREDERICK SINCLAIR CORRIGAN.
